ABSTRACT: A heat exchanger comprising helically wound tubes mounted upon a support structure comprising striplike support members apertured and slotted at intervals along their length, and attachment members which are mounted upon the support members by entering arms on the attachment members through the slots and sliding the former to a desired position on the support member. The attachment members have supporting surfaces for receiving the tubes and a boss which fits into an aperture into an adjacent support member.

HEAT EXCHANGERS

BACKGROUND TO THE INVENTION

This invention relates to heat exchangers and has particular although not exclusive reference to heat exchangers of the helical type, that is, to heat exchangers in which one of the heat transfer media is contained within one or more helically wound tubes. Where two or more helically wound tubes are used they are arranged in two or more coextensive layers.

Although heat exchangers comprising helically wound plain, small-bore tubes have a high heat transfer capacity per unit volume, such heat exchangers have found only limited application because the cost of assembly is prohibitively high. The tubes must be supported to maintain them in a required, fixed relationship and it is known to use a support assembly comprising three support plates disposed radially with respect to the axis of the helically wound tubes. Each plate has a matrix of holes drilled in it at spaces corresponding to the helix lead and to the lateral spacing of adjacent helices. The radially innermost tube helix is fitted by rotating it axially and feeding its leading end in succession through the corresponding holes in the three support plates. A weld or some other mechanical lock is formed, at each hole, between tube and plate, and the process is repeated for each tube helix until the entire heat exchanger has been built up. Such a method is clearly extremely time-consuming and therefore costly.

Similar problems arise in heat exchangers whose tubes are in other configurations than helical although sometimes in a less acute form.

It is an object of the present invention to provide a construction of heat exchanger which is easier and cheaper to assemble than the construction just described.

SUMMARY OF THE INVENTION

A heat exchanger according to the invention comprises a plurality of tubes, a plurality of support members arranged substantially transversely of the tubes and a plurality of attachment members securing the tubes to the support members, the tubes being arranged in parallel layers with support members between adjacent layers, and the attachment members of one layer of tubes being used to carry the support members of the next adjacent layer of tubes.

The attachment members may comprise clips adapted to secure one, two or more adjacent tubes to the support.

The heat exchanger may comprise a plurality of tubes, a plurality of support members arranged substantially transversely of the tubes and a plurality of attachment members securing the tubes to the support members. In one example of the invention the tubes are provided substantially in the form of helices.

The term "helix" is not used in a strictly mathematical sense but is intended to cover any generally helical configuration whether of circular transverse cross section or square, rectangular, elliptical or other shape. Moreover, a tube of helical form may be deliberately distorted in different directions at successive points of support along its length, in order to induce position retaining stressing at the support points in order to derive a position retention force; such systems are described in greater detail in copending application 37398/68.

The attachment members may consist of clips having one or more curved parts which engage the tube and a base part which is secured to the support member. The clip may be of integral construction or the curved part or parts may be separate from the base part.

The or each curved part may be resilient.

Preferably, each clip is so formed that it has a surface for receiving a support member of the next adjacent group. For example the support members may be strips apertured at regular intervals in which case the clips may have bosses, a support member being mounted upon adjacent clips by entering the bosses on the latter into the holes in the strip.

The tubes may contain fissile material in which case the heat exchanger becomes a fuel element which may be helical. In this case heat is exchanged between the fissile material and coolant circulated past the tubes.

One method of assembling a heat exchanger embodying the invention comprises the steps of temporarily positioning a first group of support members, entering a first substantially helically wound tube over the first group, securing the first helix to the support members of the first group, positioning a second group of support members round and spaced from the first tube, entering a second substantially helically wound tube over the second group, and securing the second tube to the support members of the second group.

According to this method the heat exchanger is built outwards by starting at an innermost point, adding intermediate tubes and fixing the outermost tube last of all.

Alternatively, construction may proceed in an inward direction. The first tube to be positioned would thus be the outermost one. This method comprises the steps of temporarily positioning a first group of support members, entering a first substantially helically wound tube into the first group, securing the first tube to the support members of the first group, entering a second group of support members into the first helix, entering a second substantially helically wound tube into the second group of support members, and securing the second tube to the support members of the second group.

If a helix intermediate between the inner and outer helices is chosen as the starting point, construction may be carried out by the use of both methods concurrently or sequentially. It should be noted that the choice of construction method is not necessarily related to the type of attachment used for fixing the tube to the support strip.

BRIEF DESCRIPTION OF THE DRAWINGS

FIG. 1 is an end view of a first embodiment in diagrammatic form only.

FIG. 2 is a section on the line II-II of FIG. 1,

FIGS. 3 and 4 are front and side views respectively of part of a support member,

FIG. 5 is a section on the line V-V of FIG. 3,

FIGS. 6, 7 and 8 are top, side and front views respectively of an attachment member,

FIG. 9 is a side view of part of the first embodiment after assembly,

FIGS. 10, 11 and 12 are front, plan and side views respectively of part of another form of attachment member,

FIGS. 13, 14 are side and front views respectively of another part of the other form of attachment member, and

FIG. 15 is a side view of part of the second embodiment after assembly.

DESCRIPTION OF THE PREFERRED EMBODIMENTS

FIGS. 1 and 2 show an assembled heat exchanger in diagrammatic form only. The heat exchanger comprises an outer cylindrical shell 1 and an inner cylindrical shell 2 interconnected at their ends by three radial beams 3. The annulus defined by the shells 1, 2 contains a plurality of coaxial helically wound tubes 4 each of which is supported by a group of support members each comprising an elongated strip 5 suspended from the uppermost beams 3. Each tube is attached to the support member of its supporting group by attachment means not shown in FIGS. 1 and 2.

It should be noted that the various helically wound tubes may or may not be interconnected, that they may be of differing lead, that is, helix angle, although the pitches are preferably the same, and they may or may not extend the full length of the boilers. It is not necessary that the helices should all be wound in the same direction.

Referring first to FIGS. 3, 4 and 5, each elongated support member comprises a long stainless steel strip 6 having holes 7 drilled through it at regularly-spaced intervals. In section the strip is stepped along each long side as at 8 in FIG. 5 and the

long sides are slotted at regularly-spaced intervals as indicated at 9.

The attachment members to be used with the support member just described are each clips of the form shown in FIGS. 6, 7 and 8. Each clip which is made from the material known as Nimonic 80A has curved tube grips 10 which extend from a central part 11 which is slotted as at 12, the ends of the part being inturned as at 13. The face of the clip is stepped as at 14 and has a central boss 15 beveled at 16 whose height is just slightly less than the maximum thickness of strip 6.

To assemble the heat exchanger, the innermost helically wound tube is dealt with first. Three strips 6 are to be used to support the helix and these strips are held temporarily in the positions they will occupy on completion of the entire assembly. The helix is then slid down over the three strips and temporarily supported in position. Tube support clips are then engaged with the helix by springing the grips 10 over adjacent turns of the helix close to the point of attachment to the support plate and then mounted upon the latter by passing the in-turned ends 13 through a convenient slot 9 and sliding the clip along the strip until the attachment point is reached. This process is repeated until all the turns are clipped to each support plate every time they pass it. This is shown in FIG. 9 where adjacent turns 17, 18, 19 and 20 of the helix are clipped by clips 21 and 22 to a support strip 23.

The three further support strips are now assembled by positioning them so that the bosses 15 of the clips already in position mate with the holes 7 of the further strips. The further support strips are now attached, preferably by welding, to the bosses of the innermost layer of clips. The next innermost helix is then slid over the three further support strips and fixed to the latter by further clips. This is shown in FIG. 9. Adjacent turns of the next innermost helix are shown at 24, 25 and 26 and are clipped to support strip 27 by clips 28, 29 the support strip 27 having been welded to the bosses of clips 21, 22 as indicated at 30.

The procedure is then repeated for each succeeding helix. FIG. 9 shows turns of two further helices 31, 32 secured by clips 33, 34 to support strips 35, 36 respectively.

The inner shell is then inserted through the assembled helices, and the outer shell positioned round the helices. The radial beams are then placed in position and secured to the shells and to the support strips.

The attachment clip need not be of integral construction and an alternative clip of two part construction will now be described.

The clip has a body part 37 shown in FIGS. 10, 11 and 12 having a slot 38 and inturned ends 39. A boss 40 extends centrally from face 41 of the body.

The grip portion of the clip is separate and is shown in FIGS. 13 and 14. It comprises a metal sheet 42 bent into the form of a shallow U and has a central hole 43.

Conveniently, the body of the clip is of stainless steel whilst the clip is of material known as Nimonic 80A.

The assembly of the composite clip will now be described with reference to FIG. 15. The innermost group of support strips 44 is positioned, and the innermost helix 45 positioned around the group. The body parts 37 are lockingly engaged with the support strips 44, and the clip parts 42 have their holes 43 engaged on bosses 40 of the body parts. Note that no positive jointing operative has been performed up to this stage to assemble the two part clip.

The second row 46 of support strips is positioned by engaging the holes therein with the bosses 40. The bosses 40 are now welded to the second support strips 46, this weld thus forms the dual function of attaching the second support strips to the assembly, and of attaching to each other the two parts of the clip. It may be preferable, for example when the external heat transfer fluid is a reactor coolant gas, and for where the boiler is relatively inaccessible, to avoid the "loose" or

clearance fit between the clip body part 37 (or grips 10) and the support strip 44 in view of the risk of corrosion fretting occurring at the contacting surfaces. One way in which this may be achieved is to weld the body parts 37 (or grips 10) to the support strips 44 at a number of staggered positions, and, at the remaining positions, to dispense entirely with the "stirrup" connection to the adjacent strip. Thus, all potential fretting is eliminated, and, by leaving out some of the interconnections and staggering the remainder, a support system is built up which is flexible in the radial direction. This flexibility is desirable to prevent excessive stress, due to thermal expansion, being induced in the tubes. Such stress might otherwise occur because the thermal expansion of the support members (having a temperature range of room temperature to primary heat transfer temperature) is greater than that of the tubes (which have a temperature range of room temperature to secondary heat transfer temperature). The relative expansions of the tubes and support members will also depend on the difference between the thermal properties of the materials from which they are constructed.

The embodiments described above are vertically orientated, but the invention is obviously applicable to any orientation; for example, if the axis was horizontal the tube support plates would either be considerably strengthened, or would be supported intermediate their ends.

The tube clips illustrated both hold adjacent turns of a helix; clearly each turn could have a single clip, or more than two adjacent turns could be supported by a single clip.

The invention has been described in relation to a system in which the innermost coil is positioned first; given a large enough inner diameter of the inner support cylinder, the components and assembly procedure could be reversed and built from the outside inwards. It is conceivable, in order to reduce the construction time to work from an intermediate coil and build both outwardly and inwardly concurrently.

It will be understood that regularity of the lead and pitch of the helices is not essential. The support system can readily be adapted to support helices of irregular lead and pitch.

I claim:

1. A heat exchanger comprising in combination a first layer of tubes, a first series of support members of elongated form disposed transversely with respect to the tubes of the first layer, first attachment members mounted on the support members and carrying the tubes of the first layer, a second layer of tubes, a second series of support members of elongated form disposed transversely with respect to the tubes of the second layer, the support members of the second series being carried by the first attachment members, second attachment members mounted upon the support members of the second series and carrying the tubes of the second layer support members being of striplike form and having slots at spaced intervals along the length of the strip, and said attachment members having inturned parts adapted to be entered through said slots in order to mount the attachment members on the support member.
2. A heat exchanger as claimed in claim 1 in which the support members are apertured at spaced intervals along their length, and in which the attachment members have bosses which locate in the apertures to enable the attachment members to carry support members.
3. A heat exchanger as claimed in claim 2 in which each attachment member consists of a curved part which engages a tube and a base part by which the attachment member is mounted upon a support member.
4. A heat exchanger as claimed in claim 2 in which each attachment member consists of a first curved part which engages a tube and a second base part separate from the first part and by means of which the attachment member is mounted upon a support member.
